(57) **CLAIM**

The ornamental design for a gown with access port, as shown and described.

DESCRIPTION

FIG. 1 is a perspective view of a gown with access port in an untied configuration and showing our new design; FIG. 2 is a right elevation view thereof; FIG. 3 is a left elevation view thereof; FIG. 4 is a front elevation view thereof; FIG. 5 is a first rear elevation view thereof with a fold disposed along the backside of the gown concealing the access port; FIG. 6 is a top plan view of the gown with access port in the untied configuration; FIG. 7 is a plan view thereof; FIG. 8 is another perspective view of the gown with access port in the untied configuration and having a left, front flap of the gown with access port folded open to expose a right, front flap of the gown with access port; FIG. 9 is another perspective view of the gown with access port in the untied configuration and having the right, front flap of the gown with access port folded open to expose an interior of the right, front flap; FIG. 10 is another perspective view of the gown with access port in the untied configuration with both the left, front flap and the right, front flap of the gown with access port folded open to reveal one side of the access port disposed along an interior of the gown; FIG. 11 is another perspective view of the gown with access port with the fold concealing the access port along the backside of the gown; FIG. 12 is another perspective view of the gown with access port with the fold disposed along the backside of the gown unfolded to reveal another side of the access port disposed along an exterior of the backside of the gown; and, FIG. 13 is a perspective view of the gown with access port, depicted as if being worn by a user, in a tied configuration and showing our new design. The broken lines shown illustrate portions and environment of the gown with access port that form no part of the claimed design.
